UNITED STATES PATENT OFFICE.

ELMER BANGS, OF CORTLAND, NEW YORK.

COFFIN.

SPECIFICATION forming part of Letters Patent No. 378,076, dated February 21, 1888.

Application filed June 11, 1887. Serial No. 240,992. (No model.)

To all whom it may concern:

Be it known that I, ELMER BANGS, a citizen of the United States, residing at Cortland, in the county of Cortland and State of New York, have invented certain new and useful Improvements in Burial-Caskets, of which the following is a specification, reference being had therein to the accompanying drawings.

This invention relates to the class of burial-casket lids which are designed to be self-supporting in an open position on the casket rectilinearly and at right angles to the casket; and the invention consists in a novel construction and combination of a lid composed of sections adapted to fold one upon the other and to slide on top of the casket, all as hereinafter more fully described, and specifically set forth in the claim.

In the annexed drawings, Figure 1 is a perspective view of a burial-casket embodying my invention. Fig. 2 is an enlarged transverse section of the same, and Fig. 3 is a detached plan view of one of the slotted metal plates by which the sliding section of the lid is connected with the casket.

Similar letters of reference indicate corresponding parts.

A represents the casket, and C the removable lid thereof. Said lid I divide longitudinally at the center of its width and subdivide each half thereof into longitudinal sections or panels *a b*. To the under side of the outer section, *a*, I rigidly secure the plate *c*, which is provided with transverse slots *d d*, and to the inner edge of said section I hinge the section *b*, so as to allow the latter to fold over upon the former. To the top edge of the casket A, I rigidly secure guide-pins *e e*, which project through the plates *c c* and are provided

of preventing the sliding sections *a a* from being lifted from the casket, and also to render the lid self-sustaining when in its open position.

In opening the lid the inner or central sections, *b b*, are folded outward and over onto the outer sections, *a*, and then the folded sections are slid outward on the top of the casket. The pins *e e*, sliding in the slots *d d* of the plates *c c*, serve to guide the lid sections in their aforesaid sliding movement, and the engagement of the heads of said pins with the upper sides of the plates renders the lid sections self-supporting when in their open position.

It will be observed that my improved casket-lid is simple in construction, convenient in its operation, and when open the lid lies neatly and compactly folded on the top of the sides of the casket.

Having described my invention, what I claim as new, and desire to secure by Letters Patent, is—

The combination, with a burial-casket, of a lid divided longitudinally at the center of its width and each half subdivided into longitudinal sections, the inner sections hinged to the outer sections, transversely-slotted plates secured to the outer sections, and guide-pins projecting from the top of the side walls of the casket and through the slotted plates and provided with heads above said plates, substantially as described and shown.

In testimony whereof I affix my signature in presence of two witnesses.

ELMER BANGS.
